UNITED STATES PATENT OFFICE.

HENRY H. SAVAGE, OF MOUNT HOLLY, NEW JERSEY.

BELT FOR MILITARY OR SPORTING USE.

954,006.

Specification of Letters Patent.

Patented Apr. 5, 1910.

Application filed November 9, 1908. Serial No. 461,794.

To all whom it may concern:

Be it known that I, HENRY H. SAVAGE, residing at Mount Holly, in the county of Burlington and State of New Jersey, have 5 invented certain new and useful Improvements in Belts for Military or Sporting Use, of which the following is a specification.

This invention relates to belts for military or sporting use.

10 The object of this invention is to provide a belt which is easily and quickly filled with ammunition, and which permits the ammunition to be removed from it at a point or points convenient for the wearer. It supports ammunition in such a way that it is 15 fully protected from exposure and cannot be lost.

A belt made in accordance with this invention is simple in structure and in operation 20 and inexpensive to manufacture.

Referring to the drawings, Figure 1 is a side elevation of a belt, showing discharge covers raised so that ammunition may be taken from the belt at points convenient for 25 the wearer. Fig. 2 is a section upon line 2—2 of Fig. 1. Fig. 3 is a detail view showing a side elevation of a carrier loaded with ammunition in the form of cartridges. Fig. 4 is a detail plan view of an unloaded 30 carrier.

Belt 1 is representative of any form of belt which will inclose an ammunition carrier 2. It comprises preferably a base 3, a front member 4 secured to base 3 as at 6 35 and a cover 7 connected with base 3 as at 8. In the form of embodiment of my invention shown in the drawing front member 4 is divided into two parts, but it may be undivided if that construction is preferred.

40 As shown in the drawing front member 4 is connected at its ends 9—9 and 10—10 to base 3 by side members 11—11 and 12—12; but side members 11—11 preferably do not join base 3 and front member 4 throughout 45 the full breadth of the belt, apertures 14—14 being left preferably at the upper part of the belt. Side members 12—12 join base 3 and front member 4 throughout the breadth of the belt. Since front member 4 is preferably 50 divided into two portions, cover 7 connected with base 3 at 8 is also divided into two parts 17 and 18. Parts 17 and 18 are provided preferably with snap fastenings 19 adapted to fit over projections 20 secured 55 to front member 4. At either end of the belt discharge covers 22—22 are connected with

base 3 at 24—24 and are provided preferably with snap fastenings 25 adapted to be secured to projections 26 attached to front member 4. 60

Carrier 2 is representative of any form of carrier adapted to hold a number of charges of ammunition. It preferably comprises an end portion 28 secured to members 29 which preferably form a series of double ammunition receptacles or loops 30. The ammunition shown in the drawing as contained in receptacles 30 is in the form of cartridges 31 held in sets 32 as by ammunition clips 33. Any other preferred form of ammunition 70 may however be substituted for these cartridges. Loop 30 fits closely about a set of cartridges 32 and holds it firmly in place. Straps 35, 35 are preferably secured to base 3 as at 36—36 and are provided preferably 75 with snap fastenings 37—37 adapted to be attached to projections 38—38 upon base 3. Base 3 is also provided at its ends 40 and 41 with means for securing them together, preferably, a projection 43 adapted to be held by 80 a clamp 44.

The belt is loaded and unloaded as follows. Parts 17 and 18 of cover 7 and discharge covers 22—22 are unfastened from front member 4 and raised so that carrier 85 2 holding ammunition within the loops 30 may be placed between base 3 and front member 4. Portion 28 projects through aperture 14 and is held in place by strap 35. Parts 17 and 18 are then lowered and secured to front member 4 by snap fastenings 90 19 which fit over projections 20 secured to front member 4. If discharge cover 22 is kept in its raised position, a set 32 of cartridges may be raised past it. When this 95 set of cartridges has been removed from the carrier, the carrier may be drawn forward by portion 28 until the next set of cartridges is beneath discharge cover 22. Then this set of cartridges may be removed and the 100 process of removal of sets of cartridges may be continued until the carrier is empty.

It will be seen from the foregoing description that belt 1 is provided with a pocket formed by base 3, front member 4, cover 7 105 and discharge covers 22—22 and that this pocket entirely incloses the ammunition held by carrier 2. The result is that the ammunition is not submitted to exposure and is in no danger of being lost. 110

I claim as my invention:

1. The combination with a belt, of a pocket

comprising a base, a front member, and a sectional closure-member, said pocket having a top discharge opening, also an end-opening, one of the sections of said closure-member being applied to said pocket contiguous to said end-opening and an ammunition carrier having an end extension adapted to extend through said end-opening.

2. The combination with a belt, of a pocket having a top discharge opening, also an end-opening and a sectional closure-member, one of the sections of said closure-member being applied to said pocket contiguous to said end-opening, and an ammunition carrier having an end-extension adapted to project through said end opening.

3. The combination with a belt, of a pocket provided with an opening at the top and a contiguous opening at the end, a sectional closure for the top opening, and a movable cartridge-carrier within said pocket, extended lengthwise; the said carrier projecting through the end opening from which it is adapted to be withdrawn.

25 4. The combination with a belt, of a pocket provided with an opening at the top, through which the cartridges are withdrawn, and a contiguous opening at the end, a sectional closure for the top opening, and a movable cartridge-carrier within said pocket, extended lengthwise and holding the cartridges in a vertical position; the said carrier projecting through the end opening from which it is adapted to be withdrawn.

35 5. The combination with a belt, of a pocket having a top discharge opening, also an end-opening and a sectional closure-member, one of the sections of said closure-member being applied to said pocket, contiguous to said end-opening, and an ammunition carrier having upwardly opening compartments with their entrances opposed to the top opening of said pocket, said ammunition carrier having an end-extension adapted to project through said end-opening.

6. The combination with a belt, of a pocket having a top discharge opening, also an end-opening, said pocket including a base, a front member and a sectional closure-member, one of the sections of said closure-member being applied to said pocket, contiguous to said end-opening, and an ammunition carrier having compartments opening opposite the discharge opening of said pocket, said ammunition carrier having an end-extension adapted to project through said end-opening.

7. The combination with a belt, of a pocket provided with an opening at the top and end, a sectional closure for the top opening, an endwise-movable cartridge-carrier within said pocket and extending

through the end opening, and vertically-holding cartridge-loops formed with said carrier to permit the cartridges to be withdrawn through the top-opening.

65 8. The combination with a belt of a pocket provided with an opening at the top and end arranged contiguously, a sectional closure for the top opening, a manually-operable endwise-movable cartridge-carrier within said pocket and extending through the end opening, vertically-holding cartridge-loops formed with said carrier, to permit the cartridges to be withdrawn through the top opening.

70 9. The combination with a belt, of a pocket provided with an opening at the top and end, a sectional closure for the top-opening, an endwise-movable cartridge-carrier within said pocket, and constructed to be withdrawn from said pocket through the end-opening, and a keeper for said carrier, arranged on said belt, outside of the pocket and adjacent to the end-opening thereof.

75 10. The combination with a belt, of a pocket provided with an opening at the top and end, a sectional closure for the top-opening, an endwise-movable cartridge-carrier within said pocket and constructed to be withdrawn from said pocket through the end-opening, vertically-holding cartridge-loops formed with said carrier, to permit the cartridges to be withdrawn through the top opening, and a keeper for said carrier arranged on said belt outside of the pocket and adjacent to the end-opening thereof.

80 11. A belt and a longitudinally movable carrier for ammunition supported thereby and comprising a series of vertically-opening twin-loops formed in the shape of a strap with an end-grasping portion.

100 12. The combination with a belt, of a pocket, consisting of a base, a front portion formed with a bottom in continuation of said base, and a sectional closure-member, said pocket having a top discharge opening, also an end-opening, one of the sections of said closure-member being applied to said pocket, contiguous to said end-opening, and an ammunition carrier including compartments with their openings opposed to said discharge-opening of said pocket, said carrier having an end-extension adapted to project through said end-opening, said pocket having a strap provided with a fastening adapted to engage said end-extension.

105 In testimony whereof I affix my signature in presence of two witnesses.
